(57) **CLAIM**

The ornamental design for a filament lamp, as shown and described.

DESCRIPTION

FIG. 1 is a front elevation view of a filament lamp showing the new design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a perspective view thereof.

The broken lines in the drawings illustrate portions of the filament lamp which forms no part of the claimed design.
